UNITED STATES PATENT OFFICE.

WILLIAM H. BANDS, OF SOUTHMONT BOROUGH, PENNSYLVANIA.

MUFFLER.

Application filed January 27, 1922. Serial No. 532,108.

To all whom it may concern:

Be it known that I, WILLIAM H. BANDS, a citizen of the United States, and a resident of the borough of Southmont, in the county 5 of Cambria and State of Pennsylvania, have invented certain new and useful Improvements in Mufflers; and I do hereby declare the following to be a full, clear, and exact 10 description of the invention, such as will enable others skilled in the art to which it appertains to make and use the same.

My invention relates to a muffler or silencer for use in connection with the passage of steam, vapors and gases of various 15 kinds through conducting channels and is intended to prevent the undue noise which would otherwise be occasioned thereby. In many locations the production of such noises is a disturbing element to persons or 20 workers nearby, and in the case of workers particularly prevents their hearing signals or other instructions, and at the same time the noise is nerve-racking and not conducive 25 to the personal comfort which is necessary in order that the workers may more easily produce their best efforts.

Although my invention is applicable to many forms of apparatus, as will be evident, I will, for the sake of simplicity and description 30 herein confine myself to its use in connection with a steam injector blower which is used for injecting air, mixed with steam, to a fuel bed to promote the combustion thereof, and although this may be supplied 35 to many kinds of fuel beds, the description herein relates to its use in connection with a gas producer. A steam and air injector blower is connected to a fuel bed in any suitable manner and is provided with a 40 steam supply pipe having a valve to regulate the supply of steam thereto, which steam may issue in the form of a jet or jets, and by reason of its velocity and movement it induces air, and a mixture of steam and air 45 is forced into the fuel bed, which, without my apparatus, causes a loud and roaring noise, but which my invention prevents. In order to accomplish this I provide a silencer or muffler which may be made of sheet or 50 cast metal, preferably with a number of passages of large size so as to reduce the velocity of the gases and vapors passing therethrough, and through this muffler a steam pipe, as above mentioned, is introduced and connected with the inlet of the injector blower,

Owing to the considerable surface exposed, a certain amount of steam will be condensed, which, if not provided for, would choke or partially choke the apparatus, and in order to prevent this I provide an automatic vent for the passage of the water of condensation from the apparatus. This in general consists of a hinged door adjacent to an opening in the construction, preferably at 60 the low point where water might accumulate, and when the apparatus is in operation a partial vacuum is formed therein by the action of the jet blower sufficient to close the door, but if the apparatus should be stopped 65 and the steam shut off entirely or partly, the partial vacuum would be broken and the door will drop by gravity and allow the water of condensation to escape through the opening. I may also provide a small opening without a door, which, under certain circumstances, will accomplish the same purpose.

Having thus given a general description of my invention, I will now, in order to 80 make the matter more clear, refer to the annexed sheet of drawings, which forms part of this specification, and in which like characters refer to like parts:—

Figure 1 is a side elevation of the lower 85 portion of a gas producer illustrating the application of my invention; Figure 2 is a vertical longitudinal sectional elevation of my improved muffler on a larger scale, taken on the line II—II of Figure 4; Figure 3 is a 90 side view showing the manner of attaching the muffler to the injector blower in a vertical position instead of in a horizontal position as shown in Figure 1; Figure 4 is a vertical transverse sectional elevation taken 95 on the line IV—IV of Figure 2, and Figure 5 is a detail view of the modification showing a small hole in the muffler casing to allow the escape of condensed water instead of the opening and the door of Figures 2 100 and 4.

Referring now to the characters of reference on the drawings:—1 indicates a gas producer in general, 2 the injector blower connected therewith and which may be of 105 any of the well-known or usual types of injector blowers operated by steam, air, etc. One of the types of injector blowers referred to is shown in Patent 802,931, gas producer, dated October 24th, 1905. 3 is the 110 outer flanged edge of the injector blower and 4 is my muffler attached thereto by its

flanges 5, although in certain cases my muffler may be secured to the blower by slipping the same over or within the tubular end of the blower. As illustrated, my muffler is 5 secured by means of its flange 5 to the blower flange 3 by the bolts 6, which pass therethrough, and within the muffler casing I provide a plurality of baffles 7, having flanged or bent edges 8 secured to the casing, and in each of these I provide a comparatively large hole 9, which is centrally arranged. In addition to this I also provide a plurality of holes 10 in the inner baffle 7 to provide additional outlets for the gases 10 and vapors passing therethrough, as I have found these are helpful in maintaining a proper supply of steam and gases and also in preventing vibration and noise, and between the baffles 7 I provide other baffles 11, 15 which fit tightly around the central steam pipe, each having an annular opening at its outer end between it and the casing. By reason of this staggered arrangement of openings in the baffles, the air which is 20 drawn within the muffler passes through the same in a zig-zag manner from the center to the circumference, thence back to the center and then to the circumference and so on through the central holes or openings 9 in 25 the baffles 7 and through the spaces or openings 12 arranged near the outer circumference of the baffles 11. The muffler and the passages therein are made comparatively large to reduce the velocities of gases and 30 vapors therein, which assists in preventing the noises.

In order to strengthen the parts and prevent undue vibration, I provide Z-shaped braces or stiffeners 13 secured to the adjacent baffle plates as illustrated, and also provide angle brackets 14 for securing the baffles 11 to the casing. A centrally arranged steam pipe 15 passes through the apparatus and is connected to the pipe 16, 40 which latter supplies steam to the injector blower. The inlet steam pipe 15 is provided with a regulating valve 17 as illustrated.

As illustrated in Figures 1, 2 and 4, I provide a hinged door 18 on the outside of the muffler casing and adjacent thereto is an opening 19 in the lower portion of the casing which is adapted to be opened or closed by said door. I also provide a door stop 20 which will only allow the door to be opened 55 a short distance, the door hinge being 21.

As illustrated in Figure 3, the door 22 is arranged at the low point of the apparatus, and as illustrated in Figure 5 a small opening 23 only is provided without a door. 60 These openings 19 and 23 are adapted to allow the condensed water to escape from the apparatus to prevent obstructing it, and in cases where the doors are used these doors will be closed by the partial vacuum due to 65 the operation of the blower, and when the

operation ceases the partial vacuum is broken, whereupon the door opens automatically by gravity, thus allowing the condensed water to escape. In cases where I use the smaller hole 23 without the door, this will 70 allow the water of condensation to escape when the steam is shut off, but at the same time will allow a slight ingress of air due to the partial vacuum within the apparatus during its operation. 75

The operation of my apparatus is as follows:—When it is desired to supply air and steam or water vapor to the fuel bed, the valve 17 is opened, and if desired an air regulating door (not shown) may also be adjusted to give the required amount of air opening as is customary with injector blowers. When this is done the air flows into the apparatus through the outer opening 9, passes along the baffles 7, thence through the opening 12, thence backward toward the center and through the central opening 9 in the next baffle 7 and so on in a zig-zag manner until it is supplied to the injector blower through the central opening 9 in the last baffle and also partially through the other holes or openings 10 therein. As the door 18 is closed by the partial vacuum it does not disturb the distribution of gases or vapors within the apparatus. When the air, steam and vapor supply is desired to be shut off, the valve 17 is closed, the partial vacuum is thereby broken and the pressure in the apparatus becomes the same as that of the atmosphere outside, whereupon the door 18 or 22 drops by gravity, which allows the discharge of the water of condensation. 95

In the construction shown in Figure 5, the opening 23 will at all times allow the condensed water to escape, but when the apparatus is in operation a small amount of air will also be drawn therein through the hole. 105

Although I have described and illustrated my invention in considerable detail, I do not wish to be limited to the exact and specific details thereof, as shown and described, but may use such modifications in, substitutions for, or equivalents thereof as are embraced within the scope of my invention, or 110 as pointed out in the claims. 115

Having thus described my invention, what I claim and desire to secure by Letters Patent is:—

1. The combination with an injector blower, of a muffler mounted on the inlet end thereof and provided with a plurality of zig-zag passages of comparatively large size. 120
  2. The combination with an injector blower, of a muffler mounted on the inlet end thereof, provided with a plurality of circuitous passages of comparatively large size, an opening near the bottom of said muffler, and a hinged door attached thereto adapted to close and open said opening. 125
- 130

3. The combination with an injector blower, of a muffler mounted on the inlet end thereof, provided with a plurality of circuitous passages of comparatively large size, an opening near the bottom of said muffler, a hinged door attached thereto adapted to close and open said opening, and a stop to limit the outward movement of the door.

4. The combination with an injector blower, of a muffler mounted on the inlet end thereof, a steam pipe passing through said muffler, a plurality of circuitous passages within said muffler, an opening in the lower part of the apparatus provided with a hinged door to close and open the same, and a stop to limit the outer movement of said door.

5. The combination with an injector blower, of a muffler mounted on the inlet end thereof, comprising a casing having an opening in the outer end thereof, a plurality of baffles provided with openings arranged alternately near the center and the circum-

ference of said muffler, an opening at the lower part of said muffler, a hinged door adjacent said opening and adapted to open and close the same, and a stop to limit the outer movement of the door.

6. The combination with an injector blower, of a muffler mounted on the inlet end thereof, said muffler comprising a casing having an opening in each end thereof, a plurality of baffles provided with openings arranged alternately near the center and near the circumference of said muffler, a plurality of intermediate openings in the baffle plate nearest the blower, a discharge opening at the lower part of said muffler, a hinged door adjacent said discharge opening and adapted to automatically open and close the same, and a stop to limit the outer movement of the door.

In witness whereof I hereunto affix my signature.

WILLIAM H. BANDS.
